UNITED STATES PATENT OFFICE.

CHESTER L. LINCOLN, OF NEW YORK, N. Y.

MANHOLE TOP.

Application filed November 22, 1921. Serial No. 516,923.

To all whom it may concern:

Be it known that I, CHESTER L. LINCOLN, a citizen of the United States, residing in the borough of Manhattan, city, county, and 5 State of New York, have invented certain new and useful Improvements in Manhole Tops; and I declare that the following is a full, clear, and exact description of the invention, which will enable others skilled in 10 the art to which it appertains to make and use the same.

My invention relates to manhole-tops, such as are used for street-openings, for sewers, electrical conduits and the like.

15 One of the objects of my invention is to provide a manhole-top, adjustable relatively to the surface of the street, which will be simple and economical to manufacture, and which shall be so constructed that it 20 will not accumulate dirt that will interfere with its operation or adjustability.

Another object is to secure strength and durability.

25 My invention is illustrated in the drawings, wherein Fig. 1 is a plan view having a portion of the cover broken away, and Fig. 2 is a sectional view on the line 2—2 of Fig. 1.

The present invention is intended as a 30 simplification of the construction shown in the patent to C. E. Tyler, No. 1,165,044, of December 21, 1915, wherein adjustability with reference to the street surface is one of the principal features.

35 Referring to the drawings in detail, the numeral 3 represents the masonry of the chamber to which a manhole-top is applied; 4 represents the annular base section, having an outwardly extending flange 5 resting on the masonry of the chamber, and 40 downwardly extending lugs 6 to prevent lateral displacement of the base section. On the interior surface of the base section 4 are a series of posts 7, formed integrally therewith, the tops of which are inclined as at 8, to afford bearing surfaces for the inner section now to be referred to.

The inner section 9 has an annular portion 10 slightly smaller than the main part 50 of the base section 4, so as to fit in and rotate within the latter. The lower end of the annular portion 10 has a series of cutaway portions 11, each of which has an inclination corresponding to the top of the 55 posts 7. The inner section 9 is also flanged inwardly as at 12, to provide a seat for the

cover 13 and flanged outwardly, as at 14, to limit the extent of the downward movement of the inner section within the base section 4. Stop-lugs 15 limit the upward 60 movement of the inner section, to prevent the same from jumping off the posts 7. A bracket 16 is provided to hold the bail of a cleaning-bucket. The outwardly extending lugs 17 are used as rests upon the street 65 pavement.

Among other advantages which my invention presents over the art so far as I am aware of it, is the fact that the base section 4 by reason of the plurality of posts 7 70 presents no pocket in which dirt or other material may become lodged so as to interfere with the efficient operation of the structure. In the prior art, devices similar to mine either present a plurality of such 75 pockets between adjacent ratchet projections or in grooves between annular flanges. In the disclosed embodiment of my invention, if any extraneous material should become lodged on the cam surface of one of the 80 posts 7, it would immediately be removed when the structure is adjusted to operative position.

A further advantage of my invention is that the posts 7 act as strengthening ribs 85 for the base section 4 and thus allow a great saving of material in the manufacture of that section.

The operation is obvious from the foregoing description. The inner section is rotated to bring the cover up even with the surface of the street, and, as the lugs 17 are made to rest upon the street pavement, further rotation will be prevented by frictional engagement of said lugs with the pavement. 95

Having described my invention, what I claim as new is:

1. An extension or telescopic frame adapted to be used as a manhole cover, comprising a fixed base member formed as a hollow 100 cylinder, a hollow cylindrical member telescoping therein, lugs integral with said base member and extending radially inwardly from the interior surface thereof, the upper surfaces of said lugs forming cams for moving said telescoping member axially relative to said base member, cam surfaces on the lower edge of said telescoping member for co-acting with said cam surfaces on said lugs, said lugs being relatively narrow as 110 compared to the cam surfaces on said telescoping member, said lugs also being spaced

apart circumferentially of said base member a distance approximately equal to the length of a cam surface on the telescoping member, and downwardly extending stop lugs 5 at the lower end of each of said cam surfaces.

2. In a manhole-top construction, an annular base member adapted to have its lower surface rest on the masonry of a manhole, 10 a series of vertical posts integral with said base member and projecting inwardly in cross-section from the inner annular surface of said base member, said posts having inclined top surfaces adapted to act as cams to properly adapt the manhole construction to pavements of various thicknesses, an inner annular member adapted to be supported by the upper 15 surface of a pavement and to fit rotatably into said base member, the lower edge of said inner annular member having a plurality of cam faces to correspond to the inclined tops of the posts, and downwardly extending stop 20 lugs at one end of each of said cam faces.

3. An extension or telescopic frame adapted to be used as a manhole cover, comprising a fixed base member formed as a hollow 30 cylinder, a hollow cylindrical member telescoping therein, lugs integral with said base member extending radially inwardly from the interior surface thereof and spaced apart circumferentially of said base members, the 35 upper surfaces of said lugs forming cams for moving said telescoping member axially relative to said base member, cam surfaces on the lower edge of said telescoping member for co-acting with said cam surfaces on 40 said lugs, one of said cam surfaces being of

much greater length than the cam surface of one of said lugs, and means for limiting the rotary movement of said telescoping member.

4. In a manhole-top construction, an annular base member adapted to have its lower surface rest on the masonry of a manhole, a series of vertical posts integral with said base member and projecting inwardly from the inner annular surface of said base member, 45 said posts having inclined top surfaces adapted to act as cams to properly adapt the manhole construction to pavements of various thicknesses, an inner annular member adapted to be supported by the upper 50 surface of a pavement and to fit rotatably into said base member, the lower edge of said inner annular member having a plurality of cam faces to correspond to the inclined tops of the posts, and downwardly extending stop 55 lugs at one end of each of said cam faces.

5. In a manhole-top construction, an annular base member adapted to have its lower surface rest on the masonry of a manhole, a series of vertical posts integral with said 60 base member and projecting inwardly in cross-section from the inner annular surface of said base member, said posts having top surfaces adapted to act as cams to properly adapt the manhole construction to pavements 65 of various thicknesses, an inner annular member adapted to be supported by the upper surface of a pavement and to fit rotatably into said base member, said posts being spaced apart about the base member, and a 70 plurality of cams formed at the lower edge of said inner annular member, said cams being of greater length than the top surfaces of said posts.

CHESTER L. LINCOLN.
